DESIGN FOR AN EARPHONE

Alfred L. W. Williams, Cleveland Heights, and
Donald E. Rutter, East Cleveland, Ohio, assign-
ors to The Brush Development Company,
Cleveland, Ohio, a corporation of Ohio

Application March 11, 1942, Serial No. 106,152

Term of patent 14 years

To all whom it may concern:

Be it known that we, Alfred L. W. Williams, a citizen of the United States, residing at 12415 Fair Hill Road, Cleveland Heights, in the county of Cuyahoga, and State of Ohio, and Donald E. Rutter, a citizen of the United States, residing at 1273 Coit Road, East Cleveland, in the county of Cuyahoga, and State of Ohio, have invented a new, original, and ornamental Design for an Earphone, of which the following is a specification, reference being had to the accompanying drawing, forming part thereof.

Figure 1 is an enlarged plan view of an earphone showing our new design;

Fig. 2 is a side perspective view showing the device substantially in actual size; and

Fig. 3 is a side perspective view to the same scale as Fig. 1.

The dominant features of our design are shown in full lines in the drawing.

We claim:

The ornamental design for an earphone, substantially as shown and described.

ALFRED L. W. WILLIAMS.
DONALD E. RUTTER.
